UNITED STATES PATENT OFFICE.

ELMER R. CORWIN, OF CHICAGO, ILLINOIS, ASSIGNOR TO FRANK B. COOK COMPANY,
OF CHICAGO, ILLINOIS, A CORPORATION OF ILLINOIS.

TELEPHONY.

1,185,375.

Specification of Letters Patent.

Patented May 30, 1916.

Application filed July 30, 1915. Serial No. 42,707.

To all whom it may concern:

Be it known that I, ELMER R. CORWIN, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of 10 this specification.

My invention relates to telephone exchange systems and, in one of its aspects, embraces a telephone exchange system whose telephone lines are divided into groups, exchange operators' equipment at a plurality of operators' positions, and a calling line operated distributor switch for each group of lines and common to the lines of such group for associating the equipment of any 20 of the operators, available, with the calling line employing it. These groups of lines are preferably divided into minor groups, the lines of each minor group having line switches which are preferably less in number 25 than the lines of such minor group. Each group of line switches is desirably provided with a master switch in interchangeable relation therewith for determining the switch that is to be used. Other switches are pref- 30 erably added for extending calling lines beyond the aforesaid line switches, these additional line extending switches being preferably less in number than the first switches and being desirably divided into as many 35 groups as there are major groups of lines, the added line extending switches of each group of such switches pertaining to a major group of telephone lines having associated therewith facility for establishing their asso- 40 ciation with an operator, the switches of one group being adapted for association with one operator, the switches of another group being adapted for association with another operator, etc.

As the invention is preferably practised there is provided a plurality of holding switches for each operator (each holding switch relating to a different major group of telephone lines) and a call distributor 50 switch for each major group of telephone lines whereby any holding switch may be associated with any calling line in any group so that all calling lines may have access to any operator. The various line switches and 55 line extending switches are desirably oper-

ated by calling subscribers through the intermedium of the holding switches and each operator's telephone is preferably brought into interchangeable association with her holding switches by means of automatically 60 operating switching mechanism. The first switches that operate to extend calling lines are desirably provided with wipers whose waiting contacts constitute terminals pertaining to calling lines while the additional 65 line extending switches are desirably provided with wipers whose waiting contacts are connected with the wipers for the first switches so that calling lines are initially extended by serially related switches oper- 70 ating toward the calling lines rather than away therefrom. The call distributor switches preferably also operate as master switches in their relation to the added line extending switches and also in their relation 75 to the holding switches and the operators are desirably brought into telephonic connection with calling lines by way of the line extending switches and the holding switches that are brought into telephonic connection 80 with operators through the aid of the call distributor switches.

The master switches of the system of my invention are desirably provided with circuit interrupters individual thereto and which circuit interrupters are brought into interchangeable association with the line extending switches by the master switches to effect the operation of the line extending switches, each line extending switch thus be- 85 ing temporarily associated with a circuit interrupter that is, when functioning, limited to but one line extending switch to eliminate the possibility of faulty operation and doubling up of connections.

The system of the invention also desirably includes means whereby the operators' tele- 90 phones that are to be associated with calling lines are prevented from having such association, by the equipment of calling lines, 100 during the time that switches are seeking to establish connection between calling lines and the operators whereby the operators are relieved of the noise which is attendant upon the calling line extending operation.

The system of the invention also desirably includes a master switch for interchangeable association with link connectors that are provided with signal devices individual thereto, these signal devices and their cir- 105

cuits (when associated with idle link connectors) enabling the master switches to stop in association with idle link connectors, these signal device circuits being deprived of this function when they are in abnormal condition, as when the signal, such as a lamp, is broken, so that the master switch cannot stop in association with any idle link connectors whose signal is inoperative.

10 The foregoing and other features of my invention will be more fully described in connection with the accompanying drawings in which—

Figures 1 and 2, taken collectively, diagrammatically outline the preferred embodiment of the invention; and Figs. 3 and 4, taken collectively, illustrate one form of the invention as it may be practised.

Like parts are indicated by similar characters of reference throughout the different figures.

I have chosen a thousand line exchange to demonstrate the manner in which the invention may be practised. Figs. 1 and 2 generally illustrating such an exchange. The lines are subdivided into major groups, there being five hundred lines in each major group in the example chosen. Each major group is subdivided into minor groups of preferably a hundred lines each. In Fig. 1 of the drawing two lines of each hundred line minor group are illustrated. The lines in the first minor group of the first major group may be numbered 1 to 100; the second minor group, 101 to 200, etc., as indicated in Fig. 1. The lines in the first minor group of the second major group may be numbered 301 to 400; the second minor group, 401 to 500, etc.

40 The substation equipment may be of any suitable common battery type, each substation having a telephone switch hook 1, a telephone receiver 2, a telephone transmitter 3, a call bell 4, and a condenser 5. Each line has a line relay 6, the line relays of the lines of each minor group having switch contacts that are in common connection with a line switch driving relay 7 which is thus common to the lines of the minor group to which it pertains. This relay 7 is in controlling relation to a master line switch 8 that is individual to the relay 7, there thus being one master line switch 8 for each minor group of lines and which master line switch is common to the lines of its minor group. The wipers of the switch 8 are provided with sets of waiting contacts, preferably ten, though but five sets are shown in Fig. 1. Each set of waiting contacts is individual to a line switch 9, there thus being ten such line switches for each minor group of one hundred lines, though Fig. 1 of the drawing illustrates but five switches for the sake of simplicity of illustration. The wipers of each master switch normally rest

upon some waiting contacts and place the line switch to which such contacts are individual in condition for operation. In the embodiment of the invention illustrated the operation of such line switch that is thus placed in condition for operation is effected by a calling subscriber in the minor group having such line switch, the operation of this switch continuing until the wipers thereof engage the waiting contacts pertaining to the calling line, it being understood that the wipers of each line switch 9 are provided with as many sets of waiting contacts as there are lines in the minor group to which such line switch belongs whereby each line switch may have access to each of the lines in the minor group of lines having such line switch. I do not wish to be limited, however, to the places at which the line switches have their operation initiated and controlled.

The wipers of each line switch 9, in addition to having a set of waiting contacts in the associate switch 8, also have a set of waiting contacts in each of thirty line extending switches 10 assigned to the major group having such line switch 9, the similarly positioned waiting contacts in the thirty switches 10 being in multiple connection. For lack of space the diagram, Fig. 1, illustrates but twelve line extending switches 10 per major group of five hundred lines. In the example chosen, each line extending switch 10 has fifty sets of waiting contacts, there being fifty line switches 9 in the major group having the thirty line extending switches 10. The thirty line extending switches 10 pertaining to each major group are apportioned, in equal number, among two operators A, B each of whom may handle traffic of both major groups. Figs. 1 and 2 show six switches 10 (instead of the complete quota of fifteen) of each group of thirty in association with each operator's position. The set of wipers in each switch 10 is represented by a set of waiting contacts in a call holding switch 11. There may be two such switches 11 pertaining to each operator's position A, B, one of these switches 11 at an operator's position having waiting contacts pertaining to one subgroup of fifteen line extending switches 10 relating to one major group of five hundred lines and the other of these switches 11 having waiting contacts pertaining to one sub-group of fifteen line extending switches 10 relating to the other major group of five hundred lines. By this arrangement each operator has access to all of the lines in both major groups. A call distributor switch 12 is provided for each major group of lines (each such switch 12 having the relationship of a master switch to one group of line extending switches 10 belonging to each major group of telephone lines, this relationship

being effected through the intermediation of the holding switches 11 to which the switches 12 also occupy the relationship of master switches) the wipers of each switch 12 having as many sets of waiting contacts as there are operators' positions, two in the example chosen. By this switch 12 a calling line in either major group may be associated with either operator. The upper set of waiting contacts of the upper switch 12 is individual to the upper switch 11 of operator A and the lower set of waiting contacts of the upper switch 12 is individual to the upper switch 11 of operator B. The upper set of waiting contacts of the lower switch 12 is individual to the lower switch 11 of operator A and the lower set of waiting contacts of the lower switch 12 is individual to the lower switch 11 of operator B.

As the invention is preferably practised, the wipers of the call distributor switches 12 normally rest upon a set of waiting contacts. When a call distributor switch 12 is associated with a calling line in the major group having such switch 12 (an association which is effected by the relay 7 employed by the calling line), said switch 12 associates a holding switch 11 of one operator with such calling line. The line extending switch 13 driving relay 13 individual to such employed switch 12 effects the operation of relay equipment (diagrammatically indicated at 14 in Fig. 2) individual to the call holding switch 11 of one operator that has been associated with the calling line in the major group having such employed switch 12. Mechanism of such relay equipment 14 causes the other switch 12 to associate a holding switch 11 of the other operator with lines of the other major group, by which arrangement lines of either major group are not deprived of access to an operator. The operators are provided with holding relay selector switches 15 for coupling employed holding switches 11 with their telephone equipments. The wipers of the switches 11 are normally resting in connection with some set of waiting contacts individual to some switch 10. The relay 13 pertaining to the employed switch 12 operates through the call holding switch 11 that is now coupled with the employed switch 12 to set the switch 10 (individual to the set of waiting contacts engaged by the wipers of such switch 11) into operation, the wipers of such switch 10 moving until they engage the set of waiting contacts that are connected with the wipers of the switch 9 that is coupled with the calling line in the group having the employed switch 12. After a calling line has been extended into connection with the employed switch 11, the employed switch 12 has its wipers moved into engagement with the next contacts whereafter mechanism of relay equipment 14 serves to hold the calling line until the switch 15 is moved to couple the employed switch 11 with the operator having it. The two call holding switches 11 provided for each operator are associated with thirty link connector switches 16 provided for the same operator (there being but ten of such switches 16 shown for each operator for the sake of simplicity). Each switch 16 may become connected with either of its two associated switches 11 as each switch 16 is provided with as many sets of waiting contacts as there are sets of waiting contacts in both the switches 11. There are thirty sets of waiting contacts for each switch 16 in the example chosen. Each group of thirty switches 16 is provided with a master switch 17 having as many sets of waiting contacts as there are switches 16 (thirty in the example chosen), each set of waiting contacts being individual to a switch 16. The wipers of this master switch 17 normally rest in association with some unemployed link connector which may have a suitable means for connection with called lines or other calling line extensions, one of these link connectors being illustrated with a connecting plug 18 adapted for reception within jacks 19 in extending calls. Each link connector may be provided with a lamp 20 to designate it or determine it for use. The master switch 17 will cause the signal 20 of the link connected with the master switch to glow so that the attendant operator will use only the plug or other connecting device 18 to which the glowing lamp 20 is individual. When the switch 15 has become associated with the employed holding switch 11 and when the calling line has been extended by the operation of the employed switch 10, the operator's telephone set is connected with the calling line and, if desired, the call lamp 21 may simultaneously be associated with the calling line to attract the attention of the operator if she is not at her position. Having ascertained the number of the line that is to be called, the operator will insert the plug 18 individual to the glowing lamp 20 in the jack 19 of the wanted line, whereafter the operator will manipulate the manual switch 22 to operate the switch 16, individual to the employed plug 18 and whose wipers are connected with such plug, to bring the wipers of this switch 16 into engagement with the waiting contacts that are connected with the employed waiting contacts of the employed switch 11 and the wipers of the employed switch 10. An established connection between calling and called lines thus includes waiting contacts pertaining to the calling line, the wipers of an employed switch 9 engaging these waiting contacts, the waiting contacts of the employed switch 10 that are connected with the wipers of the em- 130

ployed switch 9, the wipers of the employed switch 10, the waiting contacts of the employed switch 16 that are connected with the wipers of the employed switch 10, the 5 wipers of the employed switch 16, the connecting plug 18 individual to the wipers of the employed switch 16 and connected therewith, and the jack 19 of the called line receiving the plug 18. When the employed 10 switch 16 has moved its wipers into connection with the calling line, the wipers of switches 11 and 17 are moved into connection with the next idle waiting contacts.

The apparatus which is employed in performing the operations generally described in connection with Figs. 1 and 2 is illustrated in diagrammatic detail in Figs. 3 and 4 wherein I have illustrated two telephone lines included in the same minor group. 15 When a calling subscriber initiates a call he removes his receiver 2 preparatory to securing connection with some idle operator to extend the calling line into connection with the called line or some other calling 20 line extension. The switch hook from which the receiver has been removed establishes a circuit traceable from the common grounded battery 23 (whose illustration is repeated for the sake of simplicity), 25 through the resistance coil 24, say of one hundred ohms resistance, the upper armature switch of the cutoff relay 25 and its contact, both sides of the telephone line by way of the switch hook, receiver and transmitter at the calling station and the alternate contact of the switch hook, the lower armature switch of the cutoff relay 25, the winding of the line relay 6, to ground. The lower armature switches of the line relay 30 30 are grounded and the contacts of these armature switches that pertain to the lines of a minor group that includes the calling line are connected with the contact of the armature switch of relay 26 that is common 35 to the lines of such minor group, there being one such relay 26 for the lines of each minor group. When the line relay 6 of the calling line is energized, a circuit is established 40 traceable from its lower and grounded armature switch, through the contact of such switch, the armature switch and contact of said relay 26, the line switch driving relay 7, to the grounded battery 23. The relay 7 thereupon attracts its armature switch to 45 establish a circuit traceable from the common grounded battery 23, the line switch interrupter 27, the armature switch of this interrupter 27 and its contact, the armature switch of energized relay 7 and its contact, the upper armature switch of the deenergized relay 28 and its contact, the top wiper of the master line switch 8 and the waiting contact engaged thereby, 50 the motor magnet 29, to ground. The motor magnet is operated to turn the wipers of

the switch 9 into engagement with the waiting contacts belonging to the calling line if such wipers are not already in such engagement.— When the wipers of the switch 9 thus encounter the waiting contacts of a calling line a circuit for stopping the motor magnet 29 is established, this circuit being traceable from the grounded battery 23, the winding of relay 28, the intermediate wiper of the master line switch 8, the waiting contact engaged by this wiper, the bottom wiper of the employed switch 9, the waiting contact engaged by this wiper, the upper armature switch of energized line relay 6 belonging to the calling line and its engaged contact, to ground. The relay 28 is now energized to open a circuit for the motor magnet 29 at the upper armature switch of said relay. Another circuit is established which is traceable from the lower grounded armature switch of relay 28 and its now engaged contact, the intermediate armature switch of deenergized relay 30 and its contact the winding of relay 13 to the grounded battery 23. The relay 13 establishes a circuit 55 traceable from its upper and grounded armature switch, the contact of this switch, the top wiper of the upper call distributor switch 12, the waiting contact engaged by this wiper, the upper armature switch of relay 32 and its normal contact, the winding of relay 33, to the grounded battery 23. The energized relay 33 establishes a circuit traceable from its lower grounded armature switch, the contact engaged by this switch, 60 the bottom wiper of the lower call distributor switch 12 and the waiting contact engaged thereby, the relay 30 of this switch 12, to the grounded battery 23. The energized relay 30 establishes a circuit traceable 65 from the grounded battery 23, the motor magnet 34 of the lower switch 12 (the upper switch 12 pertaining to the major group that includes the minor group partially illustrated in Fig. 3, while the lower 70 switch 12 pertains to the other major group), the armature switch of this magnet and its contact, the bottom armature switch of relay 30 and its contact, the bottom armature switch of relay 35 and the normal contact thereof pertaining to the lower switch 11 (the two switches 11 illustrated pertaining to one operator), the two normally engaged left hand contacts of the manual switch or key 36 (usually governed by a 75 chief operator), to ground. The wipers of the lower switch 12 are moved by the motor magnet 34 into connection with the waiting contacts pertaining to the lower holding switch 11 in the next idle operator's position.

The upper call distributor switch 12, which is associated with the calling line, being in association with the upper call holding switch 11, co-operates with this latter 80

switch in causing the calling line to become connected with the wiper of some line extending switch 10, the line extending switch employed having its wipers associated with the said switch 11. The motor magnet 37 of such switch 10 is operated to move its wipers into connection with the contacts that are connected with the wipers of the switch 9 that is connected with the calling line unless the wipers of such switch 10 happen already to be connected with the waiting contacts that are individual to such switch 9. The circuit of such motor magnet 37 is traceable from ground through the winding 15 of such motor magnet, the next to the lowermost waiting contact engaged by the corresponding wiper of the upper switch 11, said wiper, the next to the uppermost wiper of the upper switch 12 and the waiting contact 20 engaged thereby, the upper armature switch of relay 38 and its contact (belonging to the upper switch 12), the lower armature switch of relay 18 and its contact (belonging to the upper switch 12), the armature 25 of the interrupter 39 and its contact (belonging to the upper switch 12), the winding of said interrupter, to the grounded battery 23. The motor magnet 37 will operate to move the wipers of the employed switch 10 until they engage the waiting contacts that are connected with the wipers of the employed switch 9 and inasmuch as the wipers of the switch 9 are now connected with the calling line, such calling line is extended 30 into connection with the wipers of the employed switch 10 inasmuch as the motor 37 will cease operation when this connection has been established. The circuit by which the motor magnet 37 is caused to cease 35 operation is traceable from the grounded battery 23, the winding of relay 38 pertaining to the upper switch 12, the intermediate wiper of this switch 12, the waiting contact engaged by this wiper, the third from 40 the bottom of the wipers pertaining to the upper switch 11, the waiting contact engaged by this wiper, the bottom wiper of the employed switch 10, the waiting contact engaged by this wiper, the bottom wiper of 45 the employed switch 9, the waiting contact engaged by this wiper, the upper armature switch of the energized line relay 6 of the calling line, the contact engaged by this armature switch, to ground. The circuit for 50 the motor magnet 37 is thus broken at the upper armature switch of the energized relay 38 that belongs to the upper switch 12. The lower armature switch of the energized relay 38 pertaining to the upper switch 12 55 establishes a circuit traceable from ground, through the five hundred ohm resistance 40, the lower armature switch of said relay 38, the contact engaged by this armature switch, the upper armature switch of the associate relay 30, the contact engaged by this armature 60 switch, the next to the bottom wiper of the upper switch 12, the contact engaged by this wiper, the upper winding of relay 35 belonging to the upper switch 11, the battery 23, to ground. The latter relay 35 being energized, establishes a circuit traceable from the grounded battery 23, through the upper winding of this relay 35, (of preferably two hundred fifty ohms resistance), the top armature switch of this relay 35, the contact engaged thereby, the top armature switch of the associate relay 41, the contact engaged by this latter armature switch, the next to the top wiper of the upper switch 11, the contact engaged by this wiper, the top wiper of the employed switch 10, the waiting contact engaged by this wiper, the top wiper of the employed switch 9, the waiting contact engaged by this latter wiper, both sides of the calling line and the telephone receiver, transmitter and switch hook at the calling station, the next to the top wiper of the employed switch 9 by way of the waiting contact engaged thereby, the next to the top wiper of the employed switch 10 and the waiting contact engaged thereby, the third from the top wiper of the upper switch 11 and the waiting contact engaged thereby, the upper intermediate armature switch of the relay 41 pertaining to the upper switch 11, the contact engaged by this armature switch, the next to the top armature switch of the associate relay 35, the contact engaged by this switch, the lower winding of this relay 35, to ground. The five hundred ohm resistance 40 pertaining to the upper switch 12 being also in parallel with the lower winding of relay 35, shunts a sufficient amount of current through this relay to maintain it energized. 105

The relay 35 under discussion establishes a circuit traceable from the grounded armature switch shown immediately above the core of this relay, the contact of this armature switch, the middle wiper of the upper switch 11, the waiting contact engaged by this wiper, the lower intermediate wiper of the employed switch 10, the waiting contact engaged by this wiper, the winding of relay 42 (individual to the employed switch 9) the lower intermediate wiper of the employed switch 9, the waiting contact engaged by this wiper, the winding of the cutoff relay 25 individual to the calling line, to the grounded battery 23. The cutoff relay 25 pertaining to the calling line is now energized to open circuit through the line relay 6 of the calling line. The circuit established through the lower armature switch of this relay 6 is opened to open the circuit of relay 7 whose armature switch is released to open the circuit previously traced through the interrupter 27 and the motor magnet 29 pertaining to the employed switch 9, whereby the wipers of the employed 110

115

120

125

130

135

switch 9 are permitted to remain in connection with the calling line. The relay 42, being in the circuit through which the cutoff relay 25 of the calling line is energized, attracts its armature switch to establish a circuit traceable from ground, through this armature switch, the contact engaged by the armature switch, the lower wiper of the master line switch 8 and the waiting contact engaged thereby, the winding of relay 26, the battery 23, to ground. The bottom armature switch of relay 26 establishes an apparent circuit for the motor magnet 43 pertaining to said switch 8, whereby the wipers of this switch are moved from association with the employed switch 9 into association with some idle switch 9, the movement of the wipers of the switch 8 continuing until the bottom wiper of this switch engages a waiting contact that is disconnected from ground at some deenergized relay 42. The same interrupter 27 which was previously associated with the employed switch 9 is now associated with the new switch 9 preparatory to taking part in effecting the operation of this new switch when another call in the same minor group is initiated. By this arrangement I make the interrupter 27 common to a plurality of line switches 9 that pertain to the same minor group of telephone lines. The next to the bottom armature switch of the energized relay 35 pertaining to the upper switch 11 establishes a circuit traceable from ground, through this armature switch, the contact engaged thereby, the bottom wiper of the upper switch 12 and the contact engaged thereby, the relay 30, the battery 23, to ground. The bottom armature switch of relay 30 establishes an operating circuit for the motor magnet 44 pertaining to the upper switch 12 which is traceable from the grounded battery 23, the winding of said motor magnet, the armature switch and switch contact of this motor magnet, the bottom armature switch of the associate relay 30 and the contact engaged thereby, the bottom armature switch of the relay 35 pertaining to the upper switch 11, the normal contact of this armature switch, the two left hand contacts of the button 36 pertaining to the upper switch 11, to ground. Said motor magnet 44 is operated to bring the wipers of the upper switch 12 into connection with the new set of waiting contacts pertaining to an idle switch 11, these wipers being maintained in such connection since the circuit for the circuit closing relay 30 will be broken at the next to the bottom armature switch of relay 35 pertaining to such idle switch 11. The switch 11 thus newly associated with the upper switch 12 effects the association of the interrupter 39 of the upper switch 12 with the motor magnet 37 of a new line extending switch 10 whereby an interrupter

is made common to all of the motor magnets 37 pertaining to a major group of telephone lines.

As will be understood from the description previously given, there is a switch 11 individual to each major group of lines at each operator's position and if both of these switches 11 pertaining to a major group of lines are busy the circuit of the driving magnet 34 will be opened at the bottom armature switches of the relays 35 pertaining to these two switches 11 so that the wipers of the upper switch 12 will remain in engagement with the waiting contacts pertaining to the switch 11 last selected, this engagement continuing if the switch 11 last selected is the first to be released, but being broken if the converse is the case to associate wipers 12 with the other switch 11 that is released. The switch 11 that has become associated with the calling line is employed to bring the calling line into connection with the operator having such switch 11 and if the wipers of the holding relay selector switch 15 are not already connected with the employed switch 11 they are brought into connection therewith due to the establishment of a circuit at the bottom armature switch of relay 35 of such switch 11, this circuit being traceable from the grounded battery 23, the winding of relay 44, the upper armature switch of the previously energized relay 33 (pertaining to the employed switch 11) the contact of this armature switch, to ground. The relay 44 establishes a circuit for the motor magnet 45 of the switch 15 which is traceable from the grounded battery 23, the winding of the magnet 45, the armature switch and contact of this magnet, the armature switch of relay 44 and its contact, the lower armature switch of the relay 46 and its normal contact, to ground. When the wipers of the switch 15 have become connected with an employed switch 11, the operation of the motor magnet 45 ceases owing to the energization of relay 46 whose circuit that is thereupon established is traceable from the grounded battery 23, the winding of relay 46, the bottom wiper of switch 15 and the waiting contact engaged thereby, the alternate contact of the bottom armature switch of relay 35 belonging to the employed switch 11, said armature switch, the left hand pair of contacts belonging to the key 36 pertaining to the employed switch 11, to ground. The energized relay 46 stops the magnet 45 by breaking the circuit for this magnet at the normal contact of the bottom armature switch of relay 46. The upper armature switch of relay 46 establishes a circuit traceable from ground through this armature switch, the contact engaged thereby, the lower intermediate wiper of the switch 15, the contact engaged by this wiper, the armature switch immediately beneath

the core of relay 35 pertaining to the employed switch 11, the contact of this armature switch, the winding of relay 32, to grounded battery 23. The relay 32 of the 5 employed switch 11, being energized, opens a circuit for the relay 33 at the top armature switch of such relay 32, the upper armature switch of the relay 33, thus deenergized, opening the circuit for the relay 44 belonging to the employed switch 15 to prevent the magnet 45 from operating when the relay 46 is deenergized. The lower armature switch of said deenergized relay 33 removes ground from the bottom waiting contact of the lower 10 switch 12 to allow the wipers of this lower switch 12 to stop in connection with the lower switch 11 pertaining to the operator having the aforesaid switch 15 so that another call can lay in upon this operator's 15 position while the operator is taking care of the call about which she is receiving information through the upper switch 11.

If the exchange should be of larger capacity than that chosen as an example, each 20 operator would have more than two holding switches 11 and in such event each relay 33 would have one armature added for each additional switch 11 supplied to each operator, the circuit environment of each added 25 armature being similar to that illustrated at the bottom armature switch of each illustrated relay 33. If it should be desired to throw any switch 11 out of service the button 36 individual thereto may be depressed 30 by a chief operator to a locking position, thereby removing the ground at this button whose aid is required for the employment of the switch having the button, the ground being transferred to the right hand contact 35 of the switch 36 which is connected with the bottom waiting contact of the associate switch 12 whereby said associate switch 12 cannot have its wipers stopped upon waiting contacts that belong to the switch 11 40 whose button 36 is thus depressed. As a consequence of the association of the holding relay selector switch 15 with a call holding switch 11 circuit is established for energizing relay 47 individual to the selected 45 operator's position, this circuit being traceable from the grounded battery 23, the winding of said relay 47, the upper armature switch of relay 48 individual to the selected operator, the contact of this armature 50 switch, the armature switch of relay 49 individual to the selected operator and the contact of this armature switch, the lower armature switch of energized relay 32 of the employed switch 11, the contact of this armature switch, to ground. The lower armature 55 switch of relay 47 establishes a circuit traceable from the grounded battery 23, the winding of relay 50, the lower armature switch of relay 51 and its contact, the lower armature switch of energized relay 47 and

its contact, the alternate contact of the lower armature switch of energized relay 46, this armature switch, to ground. Relay 50 is now energized and establishes, at its upper armature switch, the illustrated local 70 circuit for the signal 21 individual to the selected operator to attract the attention of this operator if she is not at her position. The lower armature switch of relay 50 is separated from its contact to open the shunt 75 which is preferably maintained across the terminals of the operator's head telephone 52 during the operation of the switches and until the telephonic circuit between the selected operator and calling subscriber is 80 completely prepared. When this condition has been reached the operator's head telephone 52 is brought into telephonic circuit with the two top wipers of the employed switches 15, 10 and 9 and the second and 85 third wipers from the top of the employed switch 11, whereby the calling subscriber may talk to the selected operator.

The battery current for the calling subscriber is furnished from the battery 23 by 90 way of the windings of the relay 35 of the employed switch 11. The operator's transmitter 53 is provided with a connecting plug 54 receivable within a jack 55, the two terminals of the jack being connected through 95 the two windings of a relay 56, the terminals of one of which being directly grounded while the terminal of the other is grounded through the common battery 23. When the plug and jack are connected a local battery 100 circuit is established through the transmitter, this circuit including a primary coil 57 that is in inductive relation with the secondary 58 which is included in the circuit of the head telephone 52. The condenser 59 105 is in bridge of the transmitter circuit to prevent the telephonic currents from being shunted from the line by the relay 56. Condenser 60 is included in circuit with the operator's head telephone to prevent the passage of battery current therethrough. When the plug 54 is inserted within the jack 55 the relay 56 is energized, the upper armature switch of the relay 56 establishing a 110 circuit for the designating lamp 20, which circuit is traceable from the grounded battery 23, the lamp 20, the top wiper of the master cord switch 17 and the contact engaged thereby, the relay 61 desirably of one hundred ohms resistance, the upper armature switch of the energized relay 56 and its contact, to ground. The lamp 20 glows and the relay 61 is energized to move its armature switch from its normal contact into engagement with its alternate contact if the 115 filament of the lamp 20 is not broken. If the lamp 20 does not glow because of its broken filament or other open circuit condition, the relay 61 will not energize and a circuit will be established for the motor 120 125 130

magnet 62 which is traceable from the grounded common battery 23, the armature of the motor magnet 62, and its contact, the winding of magnet 62, the armature switch 5 of relay 61 and the normal contact of this armature switch, the lower armature switch of energized relay 56 and its contact, to ground. The motor magnet 62 will thereupon drive the wipers of the switch 17 until 10 the top wiper of this switch comes into connection with a perfect lamp 20 that is in normal circuit relation; whereafter the relay 61 will be energized to open the circuit of the motor magnet 62 to stop the switch 17 15 in association with the latter lamp 20 to cause it to glow.

The operator, having ascertained the number of the wanted line, will insert the plug 18, which is individual to the glowing lamp 20, in the jack 19 belonging or pertaining 20 to such wanted line. The operator will depress the button 22 to establish a circuit traceable from the ground applied at the switch 22 upon the uppermost armature 25 switch of energized relay 47, circuit continuing through the alternate contact of this armature switch, the winding of relay 51, to the grounded battery 23. The operator then releases the button 22 to remove the 30 ground there applied, a locking circuit having been established by the energized relay 51 traceable from the battery 23 through the winding of relay 51, the upper armature switch of relay 51 and its contact, the intermediate 35 armature switch of energized relay 47 and its contact, the winding of relay 63, to ground. The relay 63 is energized, a circuit being established traceable from ground, through the bottom armature switch of relay 63, the contact of this armature switch, the bottom armature switch of relay 64, the contact of this latter armature switch, next to the bottom wiper of the switch 17, the 40 waiting contact engaged by this wiper, the next to the bottom armature switch of relay 65, the contact of this armature switch, the motor magnet 66, the armature of this motor magnet, the contact of this armature, to the grounded battery 23. The motor magnet 50 66 pertains to the switch 16 whose wipers are telephonically connected with the employed plug 18, the motor magnet 66 continuing in operation until the wipers of the switch 16 engage waiting contacts that are 55 connected with the wipers belonging to the employed switch 10, it being understood that the motor magnet 66 does not operate if it should happen that the wipers of the switch 16 already are in engagement with waiting 60 contacts that are connected with the wipers of the employed switch 10. When the wipers of the switch 16 are thus engaged with waiting contacts that are connected with the wipers of the employed switch 10, the circuit for the motor magnet 66 is opened 65 at the lower armature switch of relay 64 owing to the energization of this relay which occurs due to a circuit traceable from the grounded battery 23, the winding of relay 64, the third from the bottom wiper of the switch 17, the waiting contact engaged by this wiper, the bottom wiper of the switch 16, the waiting contact engaged by this wiper, the top wiper of the employed switch 11, the waiting contact engaged by this wiper, the upper armature switch of the energized relay 32 pertaining to the employed switch 11 and the alternate contact of this armature switch, the bottom armature switch 70 of energized relay 35 pertaining to the employed switch 11 and the alternate contact 80 of this armature switch, to the grounded contact of the switch 36. The upper armature switch of energized relay 64 establishes a circuit traceable from the grounded battery 23 through the intermediate armature switch of relay 63, the contact of this armature switch, the five hundred ohm resistance 67, the upper armature switch of energized relay 64 and the contact of this armature switch, the third from the top wiper of switch 17 and the waiting contact engaged by this wiper, the lower winding of relay 65, to ground. Relay 65 is now energized to attract all of its armature switches, the two 90 top armature switches connecting the two top wipers of the switch 16 with the talking contacts of the employed plug 18, circuit through the relays 25 and 42 being now maintained at the energized relay 65. The 100 middle wiper of the switch 16 is grounded at the middle armature switch of the energized relay 65 for the purpose of maintaining the relays 42 and 25 associated with the calling line, energized. As another consequence of the energization of the relay 65, and under the assumption that the desired line is idle, a circuit is established for the 105 ringing control relay 68 which is traceable from the grounded battery 23, the third from the top of the armature switches of relay 65 and the contact engaged by this armature switch, the bottom armature switch of the busy test relay 69 (which is 110 not energized if the called line is idle) and its normal contact, the winding of relay 68, the second from the top of the wipers of switch 17 and the contact engaged thereby, the top armature switch of relay 63 and its 115 engaged contact, to ground. The top armature switch of energized relay 68 establishes a locking circuit for this relay which is traceable from the grounded battery 23, the third from the top of the armature switches of energized relay 65 and the contact engaged by this armature switch, the bottom armature switch of the busy test relay 69 and its normal contact, the winding of relay 68, the top armature switch of this relay, 120 the contact engaged by this armature switch, 125 130

the armature switch of relay 70, the normal contact of this armature switch, to ground. After the employment of the switch 11 in the process of extending a calling line, such 5 switch is moved into association with a new and idle switch 10, a result which is due to the establishment of a circuit traceable from the grounded battery 23, the relay 41 of this switch 11, the bottom wiper of this switch 10 and the waiting contact engaged thereby, the next to the bottom wiper of the employed switch 16 and the waiting contact engaged thereby, the armature switch immediately above the core of the relay 65, the 15 contact engaged thereby, to ground.

The energized relay 41 establishes a circuit traceable from the grounded armature switch immediately below the core of this relay, the contact engaged by this armature 20 switch, the armature switch and contact of motor magnet 71 of the switch 11 under discussion, the winding of this motor magnet, to the grounded battery 23. This motor magnet 71 operates until the bottom wiper 25 of said switch 11 encounters a waiting contact which is ungrounded at the next to the bottom wiper of some other and idle switch 16, this latter wiper being ungrounded when the associate relay 65 is deenergized. The 30 relay 41 of said switch 11, by attracting its two top armature switches, breaks the bridge connection by way of the relay 35, which was included across the connection established between the calling subscriber 35 and the selected operator whereby such operator is excluded from connection with the calling subscriber. The feeding of battery to the calling line, which occurred by way of the relay 35 when the operator was connected 40 with the calling line, is effected, after the exclusion of the relay 35 from circuit, by way of the battery feed relay 65. Restored armature switches of the deenergized relay 35 open all the circuits that were 45 maintained thereby to restore all apparatus in such circuits to normal. The operator's telephone equipment is now ready for connection with some new calling subscriber. The relay 48 pertaining to the switch 17 50 that was associated with the now energized relay 65 is energized by a circuit traceable from the grounded battery 23, the winding of the relay 48, the bottom wiper of the switch 17 and the waiting contact engaged 55 thereby, the bottom armature switch of the relay 65, the contact engaged by this armature switch, to ground. A circuit for the motor magnet 62 is established which is traceable from the grounded battery 23, the 60 armature switch and contact of this motor magnet, the winding of the magnet, the bottom armature switch and contact of relay 48, the armature switch and alternate contact of relay 61, the bottom armature switch 65 and contact of relay 56, to ground. The mo-

tor magnet 62 continues in operation until its bottom wiper engages a waiting contact that is ungrounded at the bottom armature switch and contact of some deenergized relay 65 associated with some idle plug 18. 70 The lamp 20 individual to such new plug 18 glows to predetermine this new plug 18 for use. The previously energized ringing control relay 68 causes the establishment of a circuit traceable from the grounded battery 23, the winding of the sluggishly releasing relay 72, the intermediate armature switch and contact of said relay 68, to ground. The energized relay 72 establishes a circuit for the cutoff relay 25 of the called 80 line, assuming that such line is idle, which is traceable from the grounded two hundred fifty ohm resistance 73, the lower intermediate armature switch of relay 72 and its alternate contact, the third or heel contact of the 85 plug 18 inserted into the jack 19 of the wanted line, the thimble of such jack, the winding of the cutoff relay 25 of the called line, to the grounded battery 23. The cutoff relay 25 of such called line attracts its 90 armature switches to prevent the line relay 6 of the called line from responding when the called subscriber responds. Another circuit established by the relay 68 is traceable from the grounded battery 23, the winding of the intermittently operated ringing relay 74, the bottom armature switch and contact of the relay 68, to the grounded interrupter 75 that intermittently establishes 95 circuit for the relay 74. The two armature switches of the ringing relay 74, which in their normal condition connect the employed plug 18 with the top wipers of the employed switch 16, are now attracted to engage their alternate contacts which are connected with 100 the source of ringing current 76 that is thus included in bridge of the called line to operate the bell 4 that is in bridge of the line at the called station owing to the engagement of the switch hook thereat with its 105 normal contact. After the called subscriber has responded and during the time that the circuit for the relay 74 is open at the interrupter 75, a circuit is established through 110 the relay 70 owing to the then deenergized condition of the relay 74. Talking battery is furnished to the called subscriber by way of said relay 70 whose energizing circuit is traceable from the grounded battery 23, the upper winding of relay 70, the top armature 115 switch and contact of relay 72, the top armature switch of relay 74 and its normal contact, the tip of the employed plug 18, the tip spring of the jack 19 engaged by the tip of the plug 18, both sides of the called line 120 and the elevated switch hook, receiver and transmitter at the called station, the sleeve spring of the employed jack 19, the sleeve contact of the plug engaging this spring, the lower armature switch of the relay 74, the 125 130

normal contact of this switch, the upper intermediate armature switch of relay 72 and the contact engaged thereby, the lower winding of relay 72 to ground.

45 The energized relay 70 opens a locking circuit for the relay 68 at the normal contact of the armature switch of relay 70; this armature switch then engaging its alternate contact to maintain the obvious circuit through relay 72. The bottom armature switch of the deenergized relay 68 opens the previously traced circuit for the relay 74 so that this relay cannot again be energized, the called subscriber having responded. The 50 calling and called parties are now in telephonic connection by a circuit which will be apparent. When the calling subscriber restores his telephone to its switch hook the switches 9, 10 and 16 that were employed in extending his line are in idle condition, all the wiper employing switches being preferably of non-restoring type. When the called subscriber restores his receiver to its switch hook, the relay 70 is reenergized to cause 55 the deenergization of relay 72 whose bottom armature switch establishes a circuit for the clearing out signal lamp 77 whose circuit was partially established at the plug seat switch contact 78 when the plug 18 was removed therefrom in being taken for use. The operator will take down the plug 18 individual to the lamp 77 and restore it into engagement with its plug seat switch 78 thereby effacing the signal conveyed by the 60 lamp 77 whereupon all of the cord equipment pertaining to the restored plug 18 is brought to normal.

If the called line is busy the relay 68 will not be energized when the operator inserts 65 the plug 18 into the jack of the busy wanted line whereupon the busy test relay 69 will be energized by a circuit traceable from the grounded battery 23, the lower winding of the busy test relay 69, the lower intermediate 70 armature switch of relay 72 and its normal contact, the heel of the plug 18, the thimble of the jack engaging the same, the multiple of this jack thimble at the operator's position where connection with the busy wanted 75 line has been established, the heel of the plug 18 at such other operator's position, the lower intermediate armature switch of energized relay 72 at such other operator's position, the alternate contact of this armature switch, to the grounded resistance 73 connected with this alternate contact. Relay 69 pertaining to the link by which connection is sought with the previously busy wanted line is now energized, this relay establishing 80 a circuit for itself traceable from ground, the upper winding of this relay, the bottom armature switch thereof, the alternate contact of this armature switch, the third from the top of the armature switches of relay 68, 85 the contact engaged by this armature switch,

to the grounded battery 23. The top armature switches of this relay 69 now include the busy tone device 79 in bridge of the line extending to the calling station to indicate to the calling subscriber that the wanted line 79 is busy.

While I have herein shown and particularly described the preferred embodiment of my invention I do not wish to be limited to the precise details of construction and 75 circuit arrangement shown as changes may readily be made without departing from the spirit of my invention, but

Having thus described my invention I claim as new and desire to secure by Letters 80 Patent the following:—

1. A telephone exchange system having telephone lines extending from substations to an exchange and which lines are subdivided into major groups with the lines of 85 the major groups divided into minor groups; line switches for the telephone lines in each minor group for taking part in the extension of calling telephone lines; a master switch individual to each minor group of telephone 90 lines for rendering operative some line switch pertaining to the minor group having such master switch; exchange operators' equipment at a plurality of operators' positions; a calling line operated distributor 95 switch for each major group of telephone lines and common to the lines of such major group for associating the equipment of any of the operators with the calling line employing it; and a plurality of holding 100 switches for each major group of telephone lines interposed between the calling line operated distributor switches and the operators' equipment for holding calling lines 105 preparatory to the connection of the equipment of selected operators therewith.

2. A telephone exchange system having telephone lines extending from substations to an exchange and which lines are subdivided into major groups with the lines of 110 the major groups divided into minor groups; line switches for the telephone lines in each minor group and less in number than such telephone lines for taking part in the extension of calling telephone lines; a master 115 switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line 120 employing it; and a plurality of holding switches for each major group of telephone lines interposed between the calling line operated distributor switches and the operators' equipment for holding calling lines 125 130

preparatory to the connection of the equipment of selected operators therewith.

3. A telephone exchange system having telephone lines extending from substations to an exchange and which lines are subdivided into major groups with the lines of the major groups divided into minor groups; line switches for the telephone lines in each minor group for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one calling line; and a plurality of holding switches for each major group of telephone lines interposed between the calling line operated distributor switches and the operators' equipment for holding calling lines preparatory to the connection of the equipment of selected operators therewith.

35 4. A telephone exchange system having telephone lines extending from substations to an exchange and which lines are divided into major groups with the lines of the major groups divided into minor groups; line switches for the telephone lines in each minor group and less in number than such 40 telephone lines for taking part in the extension of calling telephone lines; a master switch individual to each minor group of telephone lines for rendering operative some line switch pertaining to the minor group 45 having such master switch; exchange operators' equipment at a plurality of operators' positions; a calling line operated distributor switch for each major group of telephone lines and common to the lines of 50 such major group for associating the equipment of any of the operators with the calling line employing it; means whereby the calling line operated distributor switch pertaining to each major group of lines is limited to the establishment of connection between one operator's equipment and one calling line; and a plurality of holding switches for each major group of telephone lines interposed between the calling line operated distributor switches 55 and the operators' equipment for holding calling lines preparatory to the connection of the equipment of selected operators therewith.

5. A telephone exchange system having telephone lines extending from substations

to an exchange and which lines are subdivided into major groups with the lines of the major groups divided into minor groups; line switches for the telephone lines in each minor group and less in number than such telephone lines for taking part in the extension of calling telephone lines; exchange operators' equipment at a plurality of operators' positions; a calling line operated distributor switch for each major group of telephone lines and common to the lines of such major group for associating the equipment of any of the operators with the calling line employing it; and a plurality of holding switches for each major group of telephone lines interposed between the calling line operated distributor switches and the operators' equipment for holding calling lines preparatory to the connection of the equipment of selected operators therewith.

6. A telephone exchange system having telephone lines extending from substations to an exchange and which lines are divided into major groups with the lines of the major groups divided into minor groups; line switches for the telephone lines in each minor group and less in number than such telephone lines for taking part in the extension of calling telephone lines; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one calling line; and a plurality of holding switches for each major group of telephone lines interposed between the calling line operated distributor switches and the operators' equipment for holding calling lines preparatory to the connection of the equipment of selected operators therewith.

7. A telephone exchange system having telephone lines extending from substations 11 to an exchange and which lines are subdivided into groups; line switches for the telephone lines in each group and less than the number of such lines; exchange operators' equipment at a plurality of operators' 12 positions; a calling line operated distributor switch for each group of telephone lines and common to the lines of such group for associating the equipment of any of the operators with the calling line employing it; and a plurality of holding switches for each group of telephone lines interposed between the calling line operated distributor switches and the operators' equipment for holding calling lines preparatory to the connection 13

of the equipment of selected operators therewith.

8. A telephone exchange system having telephone lines extending from substations to an exchange and which lines are subdivided into groups; exchange operators' equipment at a plurality of operators' positions; a calling line operated distributor switch for each group of lines and common to the lines of such group for associating the equipment of any of the operators with the calling line employing it; and a plurality of holding switches for each group of telephone lines interposed between the calling line operated distributor switches and the operators' equipment for holding calling lines preparatory to the connection of the equipment of selected operators therewith.
9. A telephone exchange system having telephone lines extending from substations to an exchange and which lines are subdivided into groups; line switches for the telephone lines in each group and less than the number of such lines; exchange operators' equipment at a plurality of operators' positions; a calling line operated distributor switch for each group of telephone lines and common to the lines of such group for associating the equipment of any of the operators with the calling line employing it; means whereby the calling line operated distributor switch pertaining to each group of lines is limited to the establishment of connection between one operator's equipment and one calling line; and a plurality of holding switches for each group of telephone lines interposed between the calling line operated distributor switches and the operators' equipment for holding calling lines preparatory to the connection of the equipment of selected operators therewith.

10. A telephone exchange system having telephone lines extending from substations to an exchange and which lines are subdivided into groups; exchange operators' equipment at a plurality of operators' positions; a calling line operated distributor switch for each group of lines and common to the lines of such group for associating the equipment of any of the operators with the calling line employing it; means whereby the calling line operated distributor switch pertaining to each group of lines is limited to the establishment of connection between one operator's equipment and one calling line; and a plurality of holding switches for each group of telephone lines interposed between the calling line operated distributor switches and the operators' equipment for holding calling lines preparatory to the connection of the equipment of selected operators therewith.

11. A telephone exchange system having telephone lines extending from substations

to an exchange and which lines are subdivided into major groups with the lines of the major groups divided into minor groups; line switches for telephone lines in each minor group for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding calling lines preparatory to the connection of the equipment of selected operators therewith; and holding selector switches for transferring operators' telephone equipment from holding switches to holding switches.

12. A telephone exchange system having telephone lines extending from substations to an exchange and which lines are subdivided into major groups with the lines of the major groups divided into minor groups; line switches for the telephone lines in each minor group and less in number than such telephone lines for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding calling lines preparatory to the connection of the equipment of selected operators therewith; and holding selector switches for transferring operators' telephone equipment from holding switches to holding switches.

13. A telephone exchange system having telephone lines extending from substations to an exchange and which lines are subdivided into major groups with the lines of the major groups divided into minor groups; line switches for the telephone lines in each minor group for taking part in the extension of calling telephone lines; a master switch individual to each minor group of telephone lines for rendering operative

- some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one calling line; a plurality of holding switches for each major group of telephone lines interposed between the calling line operated distributor switches and the operators' equipment for holding calling lines preparatory to the connection of the equipment of selected operators therewith; and holding selector switches for transferring operators' telephone equipment from holding switches to holding switches.
14. A telephone exchange system having telephone lines extending from substations to an exchange and which lines are divided into major groups with the lines of the major groups divided into minor groups; line switches for the telephone lines in each minor group and less in number than such telephone lines for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one calling line; a plurality of holding switches for each major group of telephone lines interposed between the calling line operated distributor switches and the operators' equipment for holding calling lines preparatory to the connection of the equipment of selected operators therewith; and holding selector switches for transferring operators' telephone equipment from holding switches to holding switches.
15. A telephone exchange system having telephone lines extending from substations to an exchange and which lines are subdivided into major groups with the lines of the major groups divided into minor groups; lines switches for the telephone lines in each minor group and less in number than such telephone lines for taking part in the extension of calling telephone lines; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one calling line; a plurality of holding switches for each major group of telephone lines interposed between the calling line operated distributor switches and the operators' equipment for holding calling lines preparatory to the connection of the equipment of selected operators therewith; and holding selector switches for transferring operators' telephone equipment from holding switches to holding switches.
16. A telephone exchange system having telephone lines extending from substations to an exchange and which lines are divided into major groups with the lines of the major groups divided into minor groups; line switches for the telephone lines in each minor group and less in number than such telephone lines for taking part in the extension of calling telephone lines; exchange operators' equipment at a plurality of operators' positions; a calling line operated distributor switch for each major group of lines is limited to the establishment of connection between one operator's equipment and one calling line; a plurality of holding switches for each major group of telephone lines interposed between the calling line operated distributor switches and the operators' equipment for holding calling lines preparatory to the connection of the equipment of selected operators therewith; and holding selector switches for transferring operators' telephone equipment from holding switches to holding switches.
17. A telephone exchange system having telephone lines extending from substations to an exchange and which lines are subdivided into groups; line switches for the telephone lines in each group and less than the number of such lines; exchange operators' equipment at a plurality of operators' positions; a calling line operated distributor switch for each group of telephone lines and common to the lines of such group for associating the equipment of any of the operators with the calling line employing it; a plurality of holding switches for each group of telephone lines interposed between the calling line operated distributor switches and the operators' equipment for holding calling lines preparatory to the connection of the equipment of selected operators therewith; and holding selector switches for transferring operators' telephone equipment from holding switches to holding switches.

- of the equipment of selected operators therewith; and holding selector switches for transferring operators' telephone equipment from holding switches to holding switches.
- 5 18. A telephone exchange system having telephone lines extending from substations to an exchange and which lines are subdivided into groups; exchange operators' equipment at a plurality of operators' positions; a calling line operated distributor switch for each group of lines and common to the lines of such group for associating the equipment of any of the operators with the calling line employing it; a plurality of holding switches for each group of telephone lines interposed between the calling line operated distributor switches and the operators' equipment for holding calling lines preparatory to the connection of the equipment of selected operators therewith; and holding selector switches for transferring operators' telephone equipment from holding switches to holding switches.
19. A telephone exchange system having telephone lines extending from substations to an exchange and which lines are subdivided into groups; line switches for the telephone lines in each group and less than the number of such lines; exchange operators' equipment at a plurality of operators' positions; a calling line operated distributor switch for each group of telephone lines and common to the lines of such group for associating the equipment of any of the operators with the calling line employing it; means whereby the calling line operated distributor switch pertaining to each group of lines is limited to the establishment of connection between one operator's equipment and one calling line; a plurality of holding switches for each group of telephone lines interposed between the calling line operated distributor switches and the operators' equipment for holding calling lines preparatory to the connection of the equipment of selected operators therewith; and holding selector switches for transferring operators' telephone equipment from holding switches to holding switches.
20. A telephone exchange system having telephone lines extending from substations to an exchange and which lines are subdivided into groups; exchange operators' equipment at a plurality of operators' positions; a calling line operated distributor switch for each group of lines and common to the lines of such group for associating the equipment of any of the operators with the calling line employing it; means whereby the calling line operated distributor switch pertaining to each group of lines is limited to the establishment of connection between one operator's equipment and one calling line; a plurality of holding switches for each group of lines interposed between the calling line operated distributor switches and the operators' equipment for holding calling lines preparatory to the connection of the equipment of selected operators therewith; and holding selector switches for transferring operators' telephone equipment from holding switches to holding switches.
21. A telephone exchange system having telephone lines extending from substations to an exchange and which lines are subdivided into major groups with the lines of the major groups divided into minor groups; line switches for the telephone lines in each minor group for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding calling lines preparatory to the connection of the equipment of selected operators therewith; and calling line extending switches for extending calling lines, there being means whereby the holding switches may select and enable the operation of calling line extending switches.
22. A telephone exchange system having telephone lines extending from substations to an exchange and which lines are subdivided into major groups with the lines of the major groups divided into minor groups; line switches for the telephone lines in each minor group and less in number than such telephone lines for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding calling lines preparatory to the connection of the equipment of selected operators therewith; and calling line extending switches for extending calling lines.

there being means whereby the holding switches may select and enable the operation of calling line extending switches.

23. A telephone exchange system having 5 telephone lines extending from substations to an exchange and which lines are subdivided into major groups with the lines of the major groups divided into minor groups; line switches for the telephone lines in each 10 minor group for taking part in the extension of calling telephone lines; a master switch individual to each minor group of telephone lines for rendering operative some line switch pertaining to the minor group having 15 such master switch; exchange operators' equipment at a plurality of operators' positions; a calling line operated distributor switch for each major group of telephone lines and common to the lines of such major 20 group for associating the equipment of any of the operators with the calling line employing it; means whereby the calling line operated distributor switch pertaining to each major group of lines is limited to the establishment 25 of connection between one operator's equipment and one calling line; a plurality of holding switches for each major group of telephone lines interposed between the calling line operated distributor switches 30 and the operators' equipment for holding calling lines preparatory to the connection of the equipment of selected operators therewith; and calling line extending switches for 35 extending calling lines, there being means whereby the holding switches may select and enable the operation of calling line extending switches.

24. A telephone exchange system having 40 telephone lines extending from substations to an exchange and which lines are divided into major groups with the lines of the major groups divided into minor groups; line switches for the telephone lines in each minor group and less in number than such telephone 45 lines for taking part in the extension of calling telephone lines; a master switch individual to each minor group of telephone lines for rendering operative some line switch pertaining to the minor group having 50 such master switch; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment 55 of connection between one operator's equipment and one calling line; a plurality of holding switches for each major group of telephone lines interposed between the calling line operated distributor switches and the operators' equipment for holding calling lines preparatory to the connection of the equipment of selected operators therewith; and calling line extending switches for 60 extending calling lines, there being

tributer switches and the operators' equipment for holding calling lines preparatory to the connection of the equipment of selected operators therewith; and calling line extending switches for extending calling lines, there being means whereby the holding 70 switches may select and enable the operation of calling line extending switches.

25. A telephone exchange system having 75 telephone lines extending from substations to an exchange and which lines are subdivided into major groups with the lines of the major groups divided into minor groups; line switches for the telephone lines in each minor group and less in number than such telephone lines for taking part in the 80 extension of calling telephone lines; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling 85 line operated distributor switches and the operators' equipment for holding calling lines preparatory to the connection of the equipment of selected operators therewith; and calling line extending switches for 90 extending calling lines, there being means whereby the holding switches may select and enable the operation of calling line extending switches.

26. A telephone exchange system having 100 telephone lines extending from substations to an exchange and which lines are divided into major groups with the lines of the major groups divided into minor groups; line switches for the telephone lines in each minor group and less in number than such telephone lines for taking part in the extension of calling telephone lines; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment 105 of connection between one operator's equipment and one calling line; a plurality of holding switches for each major group of telephone lines interposed between the calling line operated distributor switches and the operators' equipment for holding calling lines preparatory to the connection of the equipment of selected operators therewith; and calling line extending switches for 110 extending calling lines, there being means whereby the calling line operated distributor switch pertaining to each major group of lines is limited to the establishment 115 of connection between one operator's equipment and one calling line; a plurality of holding switches for each major group of telephone lines interposed between the calling line operated distributor switches and the operators' equipment for holding calling lines preparatory to the connection of the equipment of selected operators therewith; and calling line extending switches for 120 extending calling lines, there being means whereby the calling line operated distributor switch pertaining to each major group of lines is limited to the establishment 125 of connection between one operator's equipment and one calling line; a plurality of holding switches for each major group of telephone lines interposed between the calling line operated distributor switches and the operators' equipment for holding calling lines preparatory to the connection of the equipment of selected operators therewith; and calling line extending switches for extending calling lines, there being

means whereby the holding switches may select and enable the operation of calling line extending switches.

27. A telephone exchange system having 5 telephone lines extending from substations to an exchange and which lines are subdivided into groups; line switches for the telephone lines in each group and less than the number of such lines; exchange operators' 10 equipment at a plurality of operators' positions; a calling line operated distributor switch for each group of telephone lines and common to the lines of such group for associating the equipment of any of the operators 15 with the calling line employing it; a plurality of holding switches for each group of telephone lines interposed between the calling line operated distributor switches and the operators' equipment for holding 20 calling lines preparatory to the connection of the equipment of selected operators therewith; and calling line extending switches for extending calling lines, there being means whereby the holding switches may 25 select and enable the operation of calling line extending switches.

28. A telephone exchange system having 30 telephone lines extending from substations to an exchange and which lines are subdivided into groups; exchange operators' 35 equipment at a plurality of operators' positions; a calling line operated distributor switch for each group of lines and common to the lines of such group for associating the equipment of any of the operators with 40 the calling line employing it; a plurality of holding switches for each group of telephone lines interposed between the calling line operated distributor switches and the operators' equipment for holding calling 45 lines preparatory to the connection of the equipment of selected operators therewith; and calling line extending switches for extending calling lines, there being means whereby the holding switches may select and enable the operation of calling line extending switches.

29. A telephone exchange system having 50 telephone lines extending from substations to an exchange and which lines are subdivided into groups; line switches for the telephone lines in each group and less than the number of such lines; exchange operators' 55 equipment at a plurality of operators' positions; a calling line operated distributor switch for each group of telephone lines and common to the lines of such group for associating the equipment of any of the operators with the calling line employing it; 60 means whereby the calling line operated distributor switch pertaining to each group of lines is limited to the establishment of connection between one operator's equipment and one calling line; a plurality of holding

switches for each group of telephone lines 65 interposed between the calling line operated distributor switches and the operators' equipment for holding calling lines preparatory to the connection of the equipment of selected operators therewith; and calling 70 line extending switches for extending calling lines, there being means whereby the holding switches may select and enable the operation of calling line extending switches.

30. A telephone exchange system having 75 telephone lines extending from substations to an exchange and which lines are subdivided into groups; exchange operators' 80 equipment at a plurality of operators' positions; a calling line operated distributor switch for each group of lines and common to the lines of such group for associating the equipment of any of the operators with the calling line employing it; means whereby the calling line operated distributor switch 85 pertaining to each group of lines is limited to the establishment of connection between one operator's equipment and one calling line; a plurality of holding switches for each group of telephone lines interposed between the calling line operated distributor 90 switches and the operators' equipment for holding calling lines preparatory to the connection of the equipment of selected operators therewith; and calling line extending switches for extending calling lines, there being means whereby the holding switches may select and enable the operation of calling line extending switches.

31. A telephone exchange system having 100 telephone lines extending from substations to an exchange and which lines are subdivided into major groups with the lines of the major groups divided into minor groups; line switches for the telephone lines 105 in each minor group for taking part in the extension of calling telephone lines; a master switch individual to each minor group of telephone lines for rendering operative some line switch pertaining to the minor 110 group having such master switch; exchange operators' equipment at a plurality of operators' positions; a calling line operated distributor switch for each major group of telephone lines and common to the lines of such major group for associating the equipment of any of the operators with the calling line employing it; a plurality of holding 115 switches for each major group of telephone lines interposed between the calling line operated distributor switches and the operators' equipment for holding calling lines preparatory to the connection of the equipment of selected operators therewith; holding 120 selector switches for transferring operators' telephone equipment from holding switches to holding switches; and line extending switches for extending calling lines, there 125

being means whereby the holding switches may select and enable the operation of calling line extending switches.

32. A telephone exchange system having 5 telephone lines extending from substations to an exchange and which lines are subdivided into major groups with the lines of the major groups divided into minor groups; line switches for the telephone lines in 10 each minor group and less in number than such telephone lines for taking part in the extension of calling telephone lines; a master switch individual to each minor group of telephone lines for rendering opera- 15 tive some line switch pertaining to the minor group having such master switch; exchange operators' equipment at a plurality of operators' positions; a calling line operated distributer switch for each major group of tele- 20 phone lines and common to the lines of such major group for associating the equipment of any of the operators with the calling line employing it; a plurality of holding switches for each major group of tele- 25 phone lines interposed between the calling line operated distributer switches and the operators' equipment for holding calling lines preparatory to the connection of the equipment of selected operators therewith; hold- 30 ing selector switches for transferring operators' telephone equipment from holding switches to holding switches; and calling line extending switches for extending calling lines, there being means whereby the hold- 35 ing switches may select and enable the operation of calling line extending switches.

33. A telephone exchange system having telephone lines extending from substations to an exchange and which lines are subdivided into major groups with the lines of the major groups divided into minor groups; line switches for the telephone lines in each minor group for taking part in the extension of calling telephone lines; a master 45 switch individual to each minor group of telephone lines for rendering operative some line switch pertaining to the minor group having such master switch; exchange operators' equipment at a plurality of opera- 50 tors' positions; a calling line operated distributer switch for each major group of telephone lines and common to the lines of such major group for associating the equipment of any of the operators with the calling line employing it; means whereby the calling line operated distributer switch pertaining to each major group of lines is limited to the establishment of connection between one operator's equipment and one call- 55 ing line; a plurality of holding switches for each major group of telephone lines interposed between the calling line operated distributer switches and the operators' equipment for holding calling lines preparatory

to the connection of the equipment of select- 65 ed operators therewith; holding selector switches for transferring operators' telephone equipment from holding switches to holding switches; and calling line extending switches for extending calling lines, there 70 being means whereby the holding switches may select and enable the operation of calling line extending switches.

34. A telephone exchange system having 75 telephone lines extending from substations to an exchange and which lines are divided into major groups with the lines of the major groups divided into minor groups; line switches for the telephone lines in each minor group and less in number than such 80 telephone lines for taking part in the extension of calling telephone lines; a master switch individual to each minor group of telephone lines for rendering operative some line switch pertaining to the minor group 85 having such master switch; exchange operators' equipment at a plurality of operators' positions; a calling line operated distributer switch for each major group of the telephone lines and common to the lines of such major group for associating the equipment of any of the operators with the calling line employing it; means whereby the calling line operated distributer switch pertaining to each major group of lines is limited to the 90 establishment of connection between one operator's equipment and one calling line; a plurality of holding switches for each major group of telephone lines interposed between the calling line operated distributer switches 95 and the operators' equipment for holding calling lines preparatory to the connection of the equipment of selected operators therewith; holding selector switches for transferring operators' telephone equipment from 100 holding switches to holding switches; and calling line extending switches for extending calling lines, there being means whereby the holding switches may select and enable the operation of calling line extending 105 switches.

35. A telephone exchange system having 110 telephone lines extending from substations to an exchange and which lines are subdivided into major groups with the lines of the major groups divided into minor groups; line switches for the telephone lines in each minor group and less in number than such 115 telephone lines for taking part in the extension of calling telephone lines; exchange 120 operators' equipment at a plurality of operators' positions; a calling line operated distributer switch for each major group of telephone lines and common to the lines of such major group for associating the equipment of any of the operators with the calling line employing it; a plurality of holding 125 switches for each major group of telephone

lines interposed between the calling line operated distributor switches and the operators' equipment for holding calling lines preparatory to the connection of the equipment of selected operators therewith; holding selector switches for transferring operators' telephone equipment from holding switches to holding switches; and calling line extending switches for extending calling lines, there being means whereby the holding switches may select and enable the operation of calling line extending switches.

33. A telephone exchange system having telephone lines extending from substations to an exchange and which lines are divided into major groups with the lines of the major groups divided into minor groups; line switches for the telephone lines in each major group and less in number than such 25 telephone lines for taking part in the extension of calling telephone lines; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining 30 to each major group of lines is limited to the establishment of connection between one operator's equipment and one calling line; a plurality of holding switches for each major group of telephone lines interposed 35 between the calling line operated distributor switches and the operators' equipment for holding calling lines preparatory to the connection of the equipment of selected operators therewith; holding selector switches 40 for transferring operators' telephone equipment from holding switches to holding switches; and calling line extending switches for extending calling lines, there being means whereby the holding switches 45 may select and enable the operation of calling line extending switches.

37. A telephone exchange system having telephone lines extending from substations to an exchange and which lines are subdivided into groups; line switches for the telephone lines in each group and less than the number of such lines; exchange operators' equipment at a plurality of operators' positions; a calling line operated distributor switch for each group of telephone lines and common to the lines of such group for associating the equipment of any of the operators with the calling line employing it; a plurality of holding switches for each group 55 of telephone lines interposed between the calling line operated distributor switches and the operators' equipment for holding calling lines preparatory to the connection of the equipment of selected operators therewith; holding selector switches for trans-

ferring operators' telephone equipment from holding switches to holding switches; and calling line extending switches for extending calling lines, there being means whereby the holding switches may select 70 and enable the operation of calling line extending switches.

38. A telephone exchange system having telephone lines extending from substations to an exchange and which lines are subdivided into groups; exchange operators' equipment at a plurality of operators' positions; a calling line operated distributor switch for each group of lines and common to the lines of such group for associating 75 the equipment of any of the operators with the calling line employing it; a plurality of holding switches for each group of telephone lines interposed between the calling line operated distributor switches and the operators' equipment for holding calling lines preparatory to the connection of the equipment of selected operators therewith; holding selector switches for transferring operators' telephone equipment from holding switches to holding switches; and calling line extending switches for extending calling lines, there being means whereby the holding switches may select and enable the operation of calling line extending switches. 80

39. A telephone exchange system having telephone lines extending from substations to an exchange and which lines are subdivided into groups; line switches for the telephone lines in each group and less than the 100 number of such lines; exchange operators' equipment at a plurality of operators' positions; a calling line operated distributor switch for each group of telephone lines and common to the lines of such group for associating the equipment of any of the operators with the calling line employing it; means whereby the calling line operated distributor switch pertaining to each group of lines is limited to the establishment of connection 105 between one operator's equipment and one calling line; a plurality of holding switches for each group of telephone lines interposed between the calling line operated distributor switches and the operators' 110 equipment for holding calling lines preparatory to the connection of the equipment of selected operators therewith; holding selector switches for transferring operators' telephone equipment from holding switches to holding switches; and calling line extending switches for extending calling lines, there being means whereby the holding switches may select and enable the operation of calling line extending switches. 115

40. A telephone exchange system having telephone lines extending from substations to an exchange and which lines are subdivided into groups; exchange operators' equipment at a plurality of operators' positions; a calling line operated distributor switch for each group of lines and common to the lines of such group for associating the equipment of any of the operators with the calling line employing it; a plurality of holding switches for each group of telephone lines interposed between the calling line operated distributor switches and the operators' equipment for holding calling lines preparatory to the connection of the equipment of selected operators therewith; holding selector switches for transferring operators' telephone equipment from holding switches to holding switches; and calling line extending switches for extending calling lines, there being means whereby the holding switches may select and enable the operation of calling line extending switches. 120

40. A telephone exchange system having telephone lines extending from substations to an exchange and which lines are subdivided into groups; exchange operators' equipment at a plurality of operators' positions; a calling line operated distributor switch for each group of lines and common to the lines of such group for associating the equipment of any of the operators with the calling line employing it; a plurality of holding switches for each group of telephone lines interposed between the calling line operated distributor switches and the operators' equipment for holding calling lines preparatory to the connection of the equipment of selected operators therewith; holding selector switches for transferring operators' telephone equipment from holding switches to holding switches; and calling line extending switches for extending calling lines, there being means whereby the holding switches may select and enable the operation of calling line extending switches. 125

- tions; a calling line operated distributor switch for each group of lines and common to the lines of such group for associating the equipment of any of the operators with the calling line employing it; means whereby the calling line operated distributor switch pertaining to each group of lines is limited to the establishment of connection between one operator's equipment and one calling line; a plurality of holding switches for each group of telephone lines interposed between the calling line operated distributor switches and the operators' equipment for holding calling lines preparatory to the connection of the equipment of selected operators therewith; holding selector switches for transferring operators' telephone equipment from holding switches to holding switches; and calling line extending switches for extending calling lines, there being means whereby the holding switches may select and enable the operation of calling line extending switches.
41. A telephone exchange system having telephone lines extending from substations to an exchange and which lines are subdivided into major groups with the lines of the major groups divided into minor groups; line switches for the telephone lines in each minor group for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding calling lines preparatory to the connection of the equipment of selected operators therewith; and calling line extending switches for extending calling lines, there being means whereby the holding switches may select and enable the operation of calling line extending switches, and call holding switches.
42. A telephone exchange system having telephone lines extending from substations to an exchange and which lines are subdivided into major groups with the lines of the major groups divided into minor groups; line switches for the telephone lines in each minor group and less in number than such telephone lines for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one calling line; a plurality of holding switches for each major group of telephone lines interposed between the calling line operated distributor switches and the operators' equipment for holding calling lines preparatory to the connection of the equipment of selected operators therewith; and calling line extending switches for extending calling lines, there being means whereby the holding switches may select and enable the operation of calling line extending switches, and bringing calling parties and operators into telephonic connection by way of employed calling line extending switches and call holding switches.
43. A telephone exchange system having telephone lines extending from substations to an exchange and which lines are subdivided into major groups with the lines of the major groups divided into minor groups; line switches for the telephone lines in each minor group for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one calling line; a plurality of holding switches for each major group of telephone lines interposed between the calling line operated distributor switches and the operators' equipment for holding calling lines preparatory to the connection of the equipment of selected operators therewith; and calling line extending switches for extending calling lines, there being means whereby the holding switches may select and enable the operation of calling line extending switches, and bringing calling parties and operators into telephonic connection by way of employed calling line extending switches and call holding switches.
44. A telephone exchange system having telephone lines extending from substations to an exchange and which lines are divided

48. A telephone exchange system having 120

telephone lines extending from substations to an exchange and which lines are subdivided into groups; exchange operators' equipment at a plurality of operators' positions; a calling line operated distributor switch for each group of lines and common to the lines of such group for associating the equipment of any of the operators with the calling line employing it; a plurality of holding switches for each group of telephone lines interposed between the calling line operated distributor switches and the operators' equipment for holding calling lines preparatory to the connection of the equipment of selected operators therewith; and calling line extending switches for extending calling lines, there being means whereby the holding switches may select and enable the operation of calling line extending switches, and for bringing calling parties and operators into telephonic connection by way of employed calling line extending switches and call holding switches.

49. A telephone exchange system having telephone lines extending from substations to an exchange and which lines are subdivided into groups; line switches for the telephone lines in each group and less than the number of such lines; exchange operators' equipment at a plurality of operators' positions; a calling line operated distributor switch for each group of telephone lines and common to the lines of such group for associating the equipment of any of the operators with the calling line employing it; means whereby the calling line operated distributor switch pertaining to each group of lines is limited to the establishment of connection between one operator's equipment and one calling line; a plurality of holding switches for each group of telephone lines interposed between the calling line operated distributor switches and the operators' equipment for holding calling lines preparatory to the connection of the equipment of selected operators therewith; and calling line extending switches for extending calling lines, there being means whereby the holding switches may select and enable the operation of calling line extending switches, and for bringing calling parties and operators into telephonic connection by way of employed calling line extending switches and call holding switches.

50. A telephone exchange system having telephone lines extending from substations to an exchange and which lines are subdivided into groups; exchange operators' equipment at a plurality of operators' positions; a calling line operated distributor switch for each group of lines and common to the lines of such group for associating the equipment of any of the operators with the calling line employing it; means whereby the calling line operated distributor switch pertaining to each group of lines is limited to the establishment of connection between one operator's equipment and one calling line; a plurality of holding switches for each group of telephone lines interposed between the calling line operated distributor switches and the operators' equipment for holding calling lines preparatory to the connection of the equipment of selected operators therewith; and calling line extending switches for extending calling lines, there being means whereby the holding switches may select and enable the operation of calling line extending switches, and for bringing calling parties and operators into telephonic connection by way of employed calling line extending switches and call holding switches.

51. A telephone exchange system having telephone lines extending from substations to an exchange and which lines are subdivided into major groups with the lines of the major groups divided into minor groups; line switches for the telephone lines in each minor group for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding calling lines preparatory to the connection of the equipment of selected operators therewith; holding selector switches for transferring operators' telephone equipment from holding switches to holding switches; and line extending switches for extending calling lines, there being means whereby the holding switches may select and enable the operation of calling line extending switches, and for bringing calling parties and operators into telephonic connection by way of employed calling line extending switches and call holding switches.

52. A telephone exchange system having telephone lines extending from substations to an exchange and which lines are subdivided into major groups with the lines of the major groups divided into minor groups; line switches for the telephone lines in each minor group and less than the number of such telephone lines for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding calling lines preparatory to the connection of the equipment of selected operators therewith; holding selector switches for transferring operators' telephone equipment from holding switches to holding switches; and line extending switches for extending calling lines, there being means whereby the holding switches may select and enable the operation of calling line extending switches, and for bringing calling parties and operators into telephonic connection by way of employed calling line extending switches and call holding switches.

- operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding calling lines preparatory to the connection of the equipment of selected operators therewith; holding selector switches for transferring operators' telephone equipment from holding switches to holding switches; and calling line extending switches for extending calling lines, there being means whereby the holding switches may select and enable the operation of calling line extending switches, and for bringing calling parties and operators into telephonic connection by way of employed calling line extending switches and call holding switches.
53. A telephone exchange system having telephone lines extending from substations to an exchange and which lines are subdivided into major groups with the lines of the major groups divided into minor groups; line switches for the telephone lines in each minor group and less in number than such telephone lines for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one calling line; a plurality of holding switches for each major group of telephone lines interposed between the calling line operated distributor switches and the operators' equipment for holding calling lines preparatory to the connection of the equipment of selected operators therewith; holding selector switches for transferring operators' telephone equipment from holding switches to holding switches; and calling line extending switches for extending calling lines, there being means whereby the holding switches may select and enable the operation of calling line extending switches, and for bringing calling parties and operators into telephonic connection by way of employed calling line extending switches and call holding switches.
54. A telephone exchange system having telephone lines extending from substations to an exchange and which lines are subdivided into major groups with the lines of the major groups divided into minor groups; line switches for the telephone lines in each minor group and less in number than such telephone lines for taking part in the extension of calling telephone lines; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding calling lines preparatory to the connection of the equipment of selected operators therewith; holding selector switches for transferring operators' telephone equipment from holding switches to holding switches; and calling line extending switches for extending calling lines, there being means whereby the holding switches may select and enable the operation of calling line extending switches, and for bringing calling parties and operators into telephonic connection by way of employed calling line extending switches and call holding switches.

atory to the connection of the equipment of selected operators therewith; holding selector switches for transferring operators' telephone equipment from holding switches to holding switches; and calling line extending switches for extending calling lines, there being means whereby the holding switches may select and enable the operation of calling line extending switches, and for bringing calling parties and operators into telephonic connection by way of employed calling line extending switches and call holding switches. 70

56. A telephone exchange system having 75 telephone lines extending from substations to an exchange and which lines are divided into major groups with the lines of the major groups divided into minor groups; line switches for the telephone lines in each 80 minor group and less in number than such telephone lines for taking part in the extension of calling telephone lines; exchange operators' equipment at a plurality of operators' positions; a calling line operated distributor switch for each major group of telephone lines and common to the lines of such major group for associating the equipment of any of the operators with the calling line employing it; means whereby the calling 85 line operated distributor switch pertaining to each major group of lines is limited to the establishment of connection between one operator's equipment and one calling line; a plurality of holding switches for each major 90 group of telephone lines interposed between the calling line operated distributor switches and the operators' equipment for holding calling lines preparatory to the connection of the equipment of selected operators therewith; holding selector switches for transferring operators' telephone equipment from holding switches to holding switches; and calling line extending switches for extending calling lines, there being means whereby the holding 95 switches may select and enable the operation of calling line extending switches, and for bringing calling parties and operators into telephonic connection by way of employed calling line extending switches and call holding switches. 100

57. A telephone exchange system having 105 telephone lines extending from substations to an exchange and which lines are subdivided into groups; line switches for the 110 telephone lines in each group and less than the number of such lines; exchange operators' equipment at a plurality of operators' positions; a calling line operated distributor switch for each group of telephone lines and common to the lines of such group for associating the equipment of any of the operators with the calling line employing it; a plurality of holding switches for each group of telephone lines interposed between the calling line operated distributor switches and the operators' equipment for holding calling lines preparatory to the connection of the equipment of selected operators therewith; holding selector switches for transferring operators' tele- 115

120 and the operators' equipment for holding calling lines preparatory to the connection of the equipment of selected operators therewith; holding selector switches for transferring operators' telephone equipment from holding switches to holding switches; and calling line extending switches for extending calling lines, there being means whereby the holding switches may select and enable the operation of calling line extending switches, and for bringing calling parties and operators into telephonic connection by way of employed calling line extending switches and call holding switches. 125

58. A telephone exchange system having 130 telephone lines extending from substations to an exchange and which lines are subdivided into groups; exchange operators' equipment at a plurality of operators' positions; a calling line operated distributor switch for each group of lines and common to the lines of such group for associating the equipment of any of the operators with the calling line employing it; a plurality of holding switches for each group of telephone 135 lines interposed between the calling line operated distributor switches and the operators' equipment for holding calling lines preparatory to the connection of the equipment of selected operators therewith; holding selector switches for transferring operators' telephone equipment from holding switches to holding switches; and calling line extending switches for extending calling lines, there being means whereby the holding switches may select and enable the operation of calling line extending switches, and for bringing calling parties and operators into telephonic connection by way of employed calling line extending switches and call holding switches. 140

59. A telephone exchange system having 145 telephone lines extending from substations to an exchange and which lines are subdivided into groups; line switches for the 150 telephone lines in each group and less than the number of such lines; exchange operators' equipment at a plurality of operators' positions; a calling line operated distributor switch for each group of telephone lines and common to the lines of such group for associating the equipment of any of the operators with the calling line employing it; means whereby the calling line operated distributor switch pertaining to each group of lines is limited to the establishment of connection between one operator's equipment and one calling line; a plurality of holding switches for each group of telephone lines interposed between the calling line operated distributor switches and the operators' equipment for holding calling lines preparatory to the connection of the equipment of selected operators therewith; holding selector switches for transferring operators' tele- 155

phone equipment from holding switches to holding switches; and calling line extending switches for extending calling lines, there being means whereby the holding switches may select and enable the operation of calling line extending switches, and for bringing calling parties and operators into telephonic connection by way of employed calling line extending switches and call holding switches.

60. A telephone exchange system having telephone lines extending from substations to an exchange and which lines are subdivided into groups; exchange operators' equipment at a plurality of operators' positions; a calling line operated distributor switch for each group of lines and common to the lines of such group for associating the equipment of any of the operators with the calling line employing it; means whereby the calling line operated distributor switch pertaining to each group of lines is limited to the establishment of connection between one operator's equipment and one calling line; a plurality of holding switches for each group of telephone lines interposed between the calling line operated distributor switches and the operators' equipment for holding calling lines preparatory to the connection of the equipment of selected operators therewith; holding selector switches for transferring operators' telephone equipment from holding switches to holding switches; and calling line extending switches for extending calling lines, there being means whereby the holding switches may select and enable the operation of calling line extending switches, and for bringing calling parties and operators into telephonic connection by way of employed calling line extending switches and call holding switches.

61. A telephone exchange system including two groups of telephone lines; line extensions for calling telephone lines; switches for extending the calling telephone lines into connection with said line extensions; exchange operators' equipment at a plurality of operators' positions; a plurality of call holding switches for each operator's position having means for associating the aforesaid switches with operators' equipment; and a call distributor switch for each group of telephone lines for selecting call holding switches pertaining to the operators' equipment, said call distributor switches having facility, operating in conjunction with call holding switches coupled therewith, for enabling the first aforesaid switches to apply extensions to calling lines.

62. A telephone exchange system including two groups of telephone lines; line extensions for calling telephone lines; switches for extending the calling telephone lines into connection with said line extensions; exchange operators' equipment at a plurality

of operators' positions; a plurality of call holding switches for each operator's position having means for associating the aforesaid switches with operators' equipment; a call distributor switch for each group of telephone lines for selecting call holding switches pertaining to the operators' equipment; and means jointly controlled by calling lines and call distributor switches in conjunction with the call holding switches coupled with the call distributor switches for enabling the operation of the first aforesaid switches.

63. A telephone exchange system including two groups of telephone lines; line extensions for calling telephone lines; switches for extending the calling telephone lines into connection with said line extensions; exchange operators' equipment at a plurality of operators' positions; a plurality of call holding switches for each operator's position having means for associating the aforesaid switches with operators' equipment; a call distributor switch for each group of telephone lines for selecting call holding switches pertaining to the operators' equipment, said call distributor switches having facility, operating in conjunction with call holding switches coupled therewith, for enabling the first aforesaid switches to apply extensions to calling lines; and means whereby a call distributor switch is prevented from becoming associated with an operator's equipment coupled with another call distributor switch.

64. A telephone exchange system including two groups of telephone lines; line extensions for calling telephone lines; switches for extending the calling telephone lines into connection with said line extensions; exchange operators' equipment at a plurality of operators' positions; a plurality of call holding switches for each operators' position having means for associating the aforesaid switches with operators' equipment; a call distributor switch for each group of telephone lines for selecting call holding switches pertaining to the operators' equipment; means jointly controlled by calling lines and call distributor switches in conjunction with the call holding switches coupled with the call distributor switches for enabling the operation of the first aforesaid switches; and means whereby a call distributor switch is prevented from becoming associated with an operator's equipment coupled with another call distributor switch.

65. A telephone exchange system including telephone lines extending to an exchange; exchange operators' equipment at an operator's position; a plurality of switches for connecting the operator's equipment with calling lines; a switch for interchangeably associating the operator's equipment with the aforesaid switches; and

means for excluding operator's equipment from circuit connection with the first aforesaid switches when they are being operated to connect the operator's equipment with calling lines and controlled by connected calling lines to permit the inclusion of the operator's telephone equipment in circuit therewith.

66. A telephone exchange system including a plurality of telephone lines extending to an exchange; link connectors at the exchange for uniting lines in conversation; signal devices individual to the link connectors; a master switch having means for coupling it with unoccupied link connectors and effecting the operation of the signal device of the link connector that is coupled with the master switch, the means for coupling the master switch with idle link connectors including the signals and their circuits whereby the master switch will not stop in association with a link connector whose signal and signal circuit are abnormal.

67. A telephone exchange system including telephone lines extending to an exchange; operators' equipment at a plurality of operators' positions; a plurality of call holding switches pertaining to each operator's position for associating the associate operator's equipment with a plurality of calling lines; and calling line operated distributor switches for maintaining later employed holding switches in condition to hold selected operators' equipment in association with calling lines while earlier employed holding switches are in service.

68. A telephone exchange system including telephone lines extending to an exchange; operators' equipment at a plurality of operators' positions; a plurality of call holding switches pertaining to each operator's position for associating the associate operator's equipment with a plurality of calling lines; calling line operated distributor switches for maintaining later employed holding switches in condition to hold selected operators' equipment in association with calling lines while earlier employed holding switches are in service; and selector switches for the operators for relating newly employed holding switches with operators' equipment when earlier employed holding switches are freed from use.

69. A telephone exchange system including telephone lines extending to an exchange; operators' equipment at a plurality of operators' positions; holding switches pertaining to the operators' positions; a calling line operated distributor switch for selecting holding switches; and means whereby the operation of the call distributor switch is prevented when there are no holding switches available for selection.

70. A telephone exchange system includ-

ing telephone lines extending to an exchange; operators' equipment at a plurality of operators' positions; holding switches pertaining to the operators' positions; a calling line operated distributor switch for selecting holding switches; means whereby the operation of the call distributor switch is prevented when there are no holding switches available for selection; and exchange operator controlled switching devices for the holding switches to render them inselectable by the call distributor switch.

71. A telephone exchange system having telephone lines extending from substations to an exchange and which lines are subdivided into major groups with the lines of the major groups divided into minor groups; line switches for the telephone lines in each minor group for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding calling lines preparatory to the connection of the equipment of selected operators therewith; calling line extending switches for extending calling lines, there being means whereby the holding switches may select and enable the operation of calling line extending switches and for bringing calling parties and operators into telephonic connection by way of the employed calling line extending switches and call holding switches; operator employed link connectors for further extending calling lines; and operator employed switches for interchangeably associating the link connectors with the conductors telephonically coupling line-extending switches with holding switches.

72. A telephone exchange system having telephone lines extending from substations to an exchange and which lines are subdivided into major groups with the lines of the major groups divided into minor groups; line switches for the telephone lines in each minor group and less in number than such telephone lines for taking part in the extension of calling telephone lines; a master switch individual to each minor group of telephone lines for rendering operative some line switch pertaining to the minor group having such master switch; exchange operators' equipment at a plurality of opera-

tors' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding calling lines preparatory to the connection of the equipment of selected operators therewith; calling line extending switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.

73. A telephone exchange system having telephone lines extending from substations to an exchange and which lines are subdivided into major groups with the lines of the major groups divided into minor groups; line switches for the telephone lines in each minor group for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one calling line; a plurality of holding switches for each major group of telephone lines interposed between the calling line operated distributor switches and the operators' equipment for holding calling lines preparatory to the connection of the equipment of selected operators therewith; calling line extending switches for extending calling lines, there being means whereby the calling line operated distributor switch pertaining to each major group of lines is limited to the establishment of connection between one operator's equipment and one calling line; a plurality of holding switches for each major group of telephone lines interposed between the calling line operated distributor switches and the operators' equipment for holding calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.

74. A telephone exchange system having telephone lines extending from substations to an exchange and which lines are divided into major groups with the lines of the major groups divided into minor groups; line switches for the telephone lines in each minor group and less in number than such telephone lines for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one calling line; a plurality of holding switches for each major group of telephone lines interposed between the calling line operated distributor switches and the operators' equipment for holding calling lines preparatory to the connection of the equipment of selected operators therewith; calling line extending switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.

75. A telephone exchange system having telephone lines extending from substations to an exchange and which lines are subdivided into major groups with the lines of the major groups divided into minor groups; line switches for the telephone lines in each minor group and less in number than such telephone lines for taking part in the extension of calling telephone lines; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines

- lines interposed between the calling line operated distributor switches and the operators' equipment for holding calling lines preparatory to the connection of the equipment of selected operators therewith; calling line extending switches for extending calling lines, there being means whereby the holding switches may select and enable the operation of calling line extending switches, 5 and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.
76. A telephone exchange system having telephone lines extending from substations to an exchange and which lines are divided into major groups with the lines of the major groups divided into minor groups; line switches for the telephone lines in each minor group and less in number than such telephone lines for taking part in the extension of calling telephone lines; exchange operators' equipment at a plurality of operators' 70 positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one calling line; a plurality of holding switches for each major group of telephone lines interposed between the calling line operated distributor switches and the operators' equipment for holding calling lines preparatory to the connection of the equipment of selected operators therewith; calling line extending switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.
77. A telephone exchange system having telephone lines extending from substations to an exchange and which lines are subdivided into groups; line switches for the telephone lines in each group and less than the number of such lines; exchange operators' 125 equipment at a plurality of operators' positions; a calling line operated distributor switch for each group of telephone lines and common to the lines of such group for associating the equipment of any of the operators with the calling line employing it; a plurality of holding switches for each group of telephone lines interposed between the calling line operated distributor switch and the operators' equipment for holding calling lines preparatory to the connection of the equipment of selected operators therewith; calling line extending switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.
78. A telephone exchange system having telephone lines extending from substations to an exchange and which lines are subdivided into groups; exchange operators' 130 positions; a calling line operated distributor switch for each group of lines and common to the lines of such group for associating the equipment of any of the operators with the calling line employing it; a plurality of holding switches for each group of telephone lines interposed between the calling line operated distributor switch and the operators' equipment for holding calling lines preparatory to the connection of the equipment of selected operators therewith; calling line extending switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.
79. A telephone exchange system having telephone lines extending from substations to an exchange and which lines are subdivided into groups; line switches for the telephone lines in each group and less than the number of such lines; exchange operators' 135 equipment at a plurality of operators' positions; a calling line operated distributor switch for each group of telephone lines and common to the lines of such group for associating the equipment of any of the operators with the calling line employing it; a plurality of holding switches for each group of telephone lines interposed between the calling line operated distributor switch and the operators' equipment for holding calling lines preparatory to the connection of the equipment of selected operators therewith; calling line extending switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.

- common to the lines of such group for associating the equipment of any of the operators with the calling line employing it; means whereby the calling line operated distributor switch pertaining to each group of lines is limited to the establishment of connection between one operator's equipment and one calling line; a plurality of holding switches for each group of telephone lines 5 interposed between the calling line operated distributor switches and the operators' equipment for holding calling lines preparatory to the connection of the equipment of selected operators therewith; calling line 10 extending switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.

80. A telephone exchange system having 30 telephone lines extending from substations to an exchange and which lines are subdivided into groups; exchange operators' equipment at a plurality of operators' positions; a calling line operated distributor switch 35 for each group of lines and common to the lines of such group for associating the equipment of any of the operators with the calling line employing it; means whereby the calling line operated distributor switch 40 pertaining to each group of lines is limited to the establishment of connection between one operator's equipment and one calling line; a plurality of holding switches for each group of telephone lines interposed between the calling line operated distributor switches and the operators' equipment for holding calling lines preparatory to the connection of the equipment of selected operators therewith; calling line 45 extending switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.

81. A telephone exchange system having 50 telephone lines extending from substations to an exchange and which lines are subdivi-

vided into major groups with the lines of the major groups divided into minor groups; line switches for the telephone lines in each minor group for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding calling lines preparatory to the connection of the equipment of selected operators therewith; holding selector switches for transferring operators' telephone equipment from holding switches to holding switches; line 55 extending switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.

82. A telephone exchange system having 60 telephone lines extending from substations to an exchange and which lines are subdivided into major groups with the lines of the major groups divided into minor groups; line switches for the telephone lines in each minor group and less in number than such telephone lines for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding calling lines preparatory to the connection of the equipment of selected operators therewith; holding selector 110 switches for transferring operators' telephone equipment from holding switches to holding switches; line 115 extending switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.

120 125 130

switches for transferring operators' telephone equipment from holding switches to holding switches; calling line extending switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.

83. A telephone exchange system having telephone lines extending from substations to an exchange and which lines are subdivided into major groups with the lines of the major groups divided into minor groups; line switches for the telephone lines in each minor group and less in number than such telephone lines for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one calling line; a plurality of holding switches for each major group of telephone lines interposed between the calling line operated distributor switches and the operators' equipment for holding calling lines preparatory to the connection of the equipment of selected operators therewith; holding selector switches for transferring operators' telephone equipment from holding switches to holding switches; calling line extending switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.

84. A telephone exchange system having telephone lines extending from substations

to an exchange and which lines are divided into major groups with the lines of the major groups divided into minor groups; line switches for the telephone lines in each minor group and less in number than such telephone lines for taking part in the extension of calling telephone lines; a master switch individual to each minor group of telephone lines for rendering operative some line switch pertaining to the minor group having such master switch; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one calling line; a plurality of holding switches for each major group of telephone lines interposed between the calling line operated distributor switches and the operators' equipment for holding calling lines preparatory to the connection of the equipment of selected operators therewith; holding selector switches for transferring operators' telephone equipment from holding switches to holding switches; calling line extending switches for extending calling lines, there being means whereby the holding switches may select and enable the operation of calling line extending switches, 70 and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.

85. A telephone exchange system having telephone lines extending from substations to an exchange and which lines are subdivided into major groups with the lines of the major groups divided into minor groups; line switches for the telephone lines in each minor group and less in number than such telephone lines for taking part in the extension of calling telephone lines; exchange operators' equipment at a plurality of operators' positions; a calling line operated distributor switch for each major group of telephone lines and common to the lines of such major group for associating the equipment of any of the operators with the calling line employing it; a plurality of holding switches for each major group of telephone lines interposed between the calling line operated distributor switches and the operators' equipment for holding

- calling lines preparatory to the connection of the equipment of selected operators therewith; holding selector switches for transferring operators' telephone equipment from
- 5 holding switches to holding switches; calling line extending switches for extending calling lines, there being means whereby the holding switches may select and enable the operation of calling line extending switches,
- 10 and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.
- 15 86. A telephone exchange system having telephone lines extending from substations to an exchange and which lines are divided into major groups with the lines of the major groups divided into minor groups;
- 20 line switches for the telephone lines in each minor group and less in number than such telephone lines for taking part in the extension of calling telephone lines; exchange operators' equipment at a plurality of operators' positions; a calling line operated distributor switch for each major group of telephone lines and common to the lines of such major group for associating the equipment of any of the operators with the calling line employing it; means whereby the calling line operated distributor switch pertaining to each major group of lines is limited to the establishment of connection between one operator's equipment and one
- 25 calling line; a plurality of holding switches for each major group of telephone lines interposed between the calling line operated distributor switches and the operators' equipment for holding calling lines preparatory to the connection of the equipment of selected operators therewith; holding selector switches for transferring operators' telephone equipment from holding switches to holding switches; calling line extending
- 30 switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the link connectors with the conductors telephonically coupling line extending switches with holding switches.
- 35 87. A telephone exchange system having telephone lines extending from substations to an exchange and which lines are divided into groups; line switches for the telephone lines in each group and less than the number of such lines; exchange operators' equipment at a plurality of operators' positions; a calling line operated distributor switch for each group of telephone lines and common to the lines of such group for associating the equipment of any of the operators with the calling line employing it; a plurality of holding switches for each group of telephone lines interposed between the calling line operated distributor switches and the operators' equipment for holding calling lines preparatory to the connection of the equipment of selected operators therewith; holding selector switches for transferring operators' telephone equipment from holding switches to holding switches; calling line extending switches for extending calling lines, there being means whereby the holding switches may select and enable the operation of calling line extending switches, and for bringing calling parties and operators into telephonic connection by way of employed calling line extending switches and call holding switches; operator employed link connectors for further extending calling lines; and operator employed switches for interchangeably associating the

link connectors with the conductors telephonically coup'ing line extending switches with holding switches.

89. A telephone exchange system having 5 telephone lines extending from substations to an exchange and which lines are subdivided into groups; line switches for the telephone lines in each group and less than the number of such lines; exchange operators' equipment at a plurality of operators' positions; a calling line operated distributor switch for each group of telephone lines and common to the lines of such group for associating the equipment of any of the operators with the calling line employing it; means whereby the calling line operated distributor switch pertaining to each group of lines is limited to the establishment of connection between one operator's equipment and one calling line; a plurality of holding switches for each group of telephone lines interposed between the calling line operated distributor switches and the operators' equipment for holding calling lines 20 preparatory to the connection of the equipment of selected operators therewith; holding selector switches for transferring operators' telephone equipment from holding switches to holding switches; calling line 25 extending switches for extending calling lines, there being means whereby the holding switches may select and enable the operation of calling line extending switches, and for bringing calling parties and operators into 30 telephonic connection by way of employed calling line extending switches and call holding switches; operator employed link connectors for further extending calling lines; and operator employed switches for 35 40 interchangeably associating the link connectors with the conductors telephonically coupling line extending switches with holding switches.

90. A telephone exchange system having

telephone lines extending from substations 45 to an exchange and which lines are subdivided into groups; exchange operators' equipment at a plurality of operators' positions; a calling line operated distributor switch for each group of lines and common 50 to the lines of such group for associating the equipment of any of the operators with the calling line employing it; means whereby the calling line operated distributor switch pertaining to each group of lines is limited 55 to the establishment of connection between one operators' equipment and one calling line; a plurality of holding switches for each group of telephone lines interposed between the calling line operated distributor switches 60 and the operators' equipment for holding calling lines preparatory to the connection of the equipment of selected operators therewith; holding selector switches for transferring operators' telephone equipment from 65 holding switches to holding switches; calling line extending switches for extending calling lines, there being means whereby the holding switches may select and enable the operation of calling line extending switches, 70 and for bringing calling parties and operators into telephonic connection by way of employed calling line extending switches and call holding switches; operator employed link connectors for further extending calling lines; and operator employed switches for 75 80 interchangeably associating the link connectors with the conductors telephonically coupling line extending switches with holding switches.

In witness whereof I hereunto subscribe my name this twenty-sixth day of July, A. D. 1915.

ELMER R. CORWIN.
